PAUL MAIWURM, OF SHREVE, OHIO.

PUNCHING AND FORMING DEVICE FOR KETTLES.

1,144,662.

Specification of Letters Patent. Patented June 29, 1915.

Application filed June 26, 1913. Serial No. 775,935.

To all whom it may concern:

Be it known that I, PAUL MAIWURM, a citizen of Germany, residing at Shreve, in the county of Wayne and State of Ohio, have invented a new and useful Punching and Forming Device for Kettles, of which the following is a specification.

My invention relates to punching and forming machines for use in the manufacture of sheet metal kettles, especially those made of aluminum; and its objects are, first, to provide speedy and convenient mechanism for punching rivet holes in the sides of such kettles opposite each other, and also at a point intermediate, simultaneously; second, to afford facilities for the proper adjustment of the several punching elements independently of each other in respect to the rim of the kettle; and, third, to provide in connection therewith co-operative means for forming the spout of such kettle simultaneously with the punching of said rivet holes. I attain these objects by the mechanism illustrated in the accompanying drawings, in which—

Figure 1 is a plan view of a machine embodying my invention; Fig. 2 is a vertical section of the same on the line X—Y of Fig. 1. Fig. 3 is a vertical section of a part of my machine on the line A—B of Fig. 2; Fig. 4 is a detailed view of one of the cam-wheels, detached; Fig. 5 is a partial view of a part of said wheel showing the relation of the two cams thereon; Fig. 6, a detailed view of one of my punch-bars, detached; and Fig. 7, a detailed view of my spout-forming device extended from the top of Fig. 3.

Similar letters and figures of reference indicate like parts.

The table plate A, its legs and standards B B, and boxings b b, which may be of any desired pattern, constitute the framework of my machine. In the boxings b b is supported a rotatable shaft C carrying two cam-wheels D E, one opposite the other, as shown in Figs. 1 and 2. Said shaft extends outwardly in one direction and is connected by a suitable clutch to power, which, being no part of the present invention, need not be further shown or described. Said shaft is mounted in such a manner as to bring the

periphery of each cam-wheel slightly above the surface of the table, as shown in Figs. 2 and 3. A third cam-wheel G is mounted 55 in like manner on a shaft F, operable in a similar boxing b at right angles with the shaft C, by beveled gear wheels 9 10, as shown in Figs. 1 and 2. The table is provided with three wings or lobes a a a, two 60 thereof being in line with the center of the table, and the other wing or lobe occupying a position at right angles with said line, as shown in Fig. 1. Upon each of the center wings is securely mounted a punch-bar I, 65 which is slideable horizontally in line with the shaft C within a channel boxing 21, being actuated in one direction by the cams 1, which stand near the margin of each cam-wheel, and, in the opposite direction, by the 70 two reciprocating slide bars 22 and 23, respectively. Said slide bars reciprocate horizontally beside each other in bearings below the table A by intermittent engagement with the cams 2, which, for the purpose, are 75 located intermediate the periphery and the center of each cam-wheel, and timed to follow the cams 1 in rotation thereon. To accomplish reciprocal movement of the punch-bars I, each of the two which are alined opposite each other as aforesaid is put into operative engagement with one of said reciprocating slide bars by a connecting arm 15 at one end thereof, the other end being provided with an anti-friction roller 3 80 85 adapted to intermittently engage said lower cam 2 as aforesaid. The several punch-bars are actuated in a forward direction in all respects alike, but the said intermediate punch-bar is reciprocally returned to normal 90 position by means of a lever 17 which is pivoted to a support extending from the table frame, and to an ear 19 on its related punch-bar, as shown in Fig. 3. The lower end of said lever is also provided with an 95 antifriction roller 20 adapted to bear against said lower cam 2, whereby, at each revolution of said cam wheel, said punch-bar is also reciprocated in both directions. Its simultaneous operation with the other 100 punch-bars is accomplished by the proper setting of said intermediate cam-wheel G upon its shaft F. A circular barrier 11, of a size suited to fit snugly within the rim of

the kettle to be punched, and provided with die openings therethrough adapted to register with the several punches $p p p$, respectively, is securely mounted upon the table center, as shown in Fig. 1. Said barrier is open on one side thereof directly opposite said intermediate punch-bar to permit the slide-bar H alined therewith to pass through said opening, said slide bar H being 10 slidable in a boxing 21, and in operative engagement with said punch-bar by a catch 24, as shown in Figs. 3 and 7. The head 16 of said slide bar is shaped and adapted to impinge against the intervening rim of said kettle by the action of said punch-bar and to reciprocate therewith. I accomplish the longitudinal adjustment of said punch-bars by making the same in two parts and regulating the distance between them by a 15 threaded bolt, having right and left threads, operable between said parts by a nut 8, as shown in Fig. 6.

The operation of the machine is such that when a kettle J is placed in inverted position upon said table with its rim about said barrier 11, by the one revolution of said cam-wheels respectively the outer cams thereof are brought into operative engagement with said punch-bars I and the anti-friction rollers 4 simultaneously, thereby actuating the punch bars I and forcing the punches p against the intervening kettle rim J and into the said dies in the barrier, whereby said rim is perforated at points opposite on one diameter thereof, and also at an intermediate point at right angles with said diameter opposite the center thereof; by the same movement, and simultaneously therewith, said slide bar H , by its engagement 20 with said intermediate punch-bar, is forced against the inner surface of said kettle rim by its head 16, which is shaped for the purpose, thereby forming a spout for said kettle at an exactly intermediate point between said opposite punch-bars, and in direct alinement with said intermediate perforation; to aid in said formation an outer barrier 14 is secured on said table, shaped to receive the impression of said head as it presses said 25 spout into its proper form thereon, at said opening 12, as shown in Figs. 1 and 7. Immediately upon the completion of said punching and forming operation the several cams 2 2 2 are brought into engagement 30 with said slide bars 22 and 23 and H , respectively, thereby withdrawing all said punch bars and said spout forming bar from said kettle and to their respective original positions, simultaneously, prepared for another operation. If desired, any one or 35 more of said punch-bars or said spout forming bar may be made inoperative, leaving the others operative as aforesaid.

By the means stated the opposite sides of

the kettle may be suitably punched, as for 40 bail ears, and, at an intermediate point, a spout may be formed therein, simultaneously, at every revolution of said cam-wheels, and such process may be repeated 45 with great exactness, perfection and rapidity, and at a minimum expense. I do not 50 limit myself to mere matter of form, and the several parts may be modified within the scope of my invention.

Having thus fully described my invention, 55 what I claim as new and desire to secure by Letters Patent is:—

1. In a machine of the character described, the combination of a pair of reciprocating punch-bars slidable operable in channels 60 alined opposite each other upon a table; a third reciprocating punch-bar slidable operable in a channel on said table at right angles with the line of said pair and midway between the same; a slidably operable 65 forming-bar alined with said third punch-bar and operatively connected thereto, provided with a forming head and adapted to reciprocate with said punch-bar between guides on said table; and a barrier mounted 70 on said table midway between said pair and equi-distant from said third punch-bar—said barrier having die perforations there-through adapted to register with the several punches of said punch-bars respectively, and 75 an opening alined with said forming bar, and a supplemental barrier adjacent said opening; die-formed to receive and engage said forming head; and means, including a series of co-acting cam-wheels, for reciprocally actuating said punch-bars and said forming-bar simultaneously, substantially 80 as set forth and for the purpose specified:

2. In a machine of the character described, a pair of punch-bars fitted with punches and 85 slidably operable reciprocally in alined channels arranged end to end on a table, equidistant from the center thereof; a punch-bar slidable operable in a channel at right angles with said pair; a forming-bar 90 in operative connection with said punch-bar and adapted to reciprocate therewith; anti-friction rollers on said punch-bars respectively; a head on said forming-bar; a die apertured barrier mounted on said table 95 equidistant from said several punch-bars, suited thereto and provided with an opening opposite the head of said forming-bar; a second barrier before said opening fitted to receive said head; a pair of cam-wheels; a shaft for the same; a third cam-wheel mounted on a shaft geared to said pair shaft at right angles therewith; a pair 100 of cams on each of said wheels, each cam following the other at different distances 105 from the centers of said wheels respectively; a pair of slide-bars reciprocally operable 110 under said table and having anti-friction

rollers; each of said slide bars operably connected to an adjacent member of said pair of punch-bars at one end, and, at the other, adapted to engage one of the pair of cams 5 on its adjacent cam-wheel; means for longitudinal adjustment of said punch-bars, and means, including a lever, for reciprocating said third punch-bar and said forming-bar

simultaneously, substantially as set forth and for the purpose specified. ¹⁰

In witness whereof, I hereunto set my hand this 23 day of June A. D. 1913.

PAUL MAIWURM.
